CLAIM

The ornamental design for a stretchable fabric cover for a container, as shown and described.

DESCRIPTION

FIG. 1 is a perspective view of a stretchable fabric cover for a container showing my new design;

FIG. 2 is a top plan view thereof;

FIG. 3 is a rear perspective view thereof; and,

FIG. 4 is a bottom plan view thereof.

The broken lines are for illustrative purposes only and form no part of the claimed design.
